OF BATTLE CREEK, MICHIGAN.

PORTABLE EMERGENCY TRAIN FLAG-STOP FOR RAILWAYS.

1,279,058.

Specification of Letters Patent. Patented Sept. 17, 1918.

Application filed April 22, 1916. Serial No. 92,862.

To all whom it may concern:

Be it known that we, WILSON E. WHITE, a citizen of the United States, residing at Detroit, in the county of Wayne and State 5 of Michigan, and BENJAMIN GWATKIN and VICTOR E. RANDALL, citizens of the United States, residing at Battle Creek, in the county of Calhoun and State of Michigan, have invented certain new and useful Im- 10 provements in Portable Emergency Train Flag-Stops for Railways, of which the following is a specification.

The present invention more particularly relates to emergency stops for use in connection with rolling stock, having specially designed apparatus to be actuated by a post or stop over which the train passes, and which will, by engaging said stop, bring the train to a halt regardless of any action at the hands 20 of the engineer or other train operative.

As ordinarily constructed, apparatus for the purpose has been fixed and limited to semaphores, targets and switches. The present invention contemplates an apparatus 25 that may be carried on the engine, tender, caboose or other car, so that should any occasion arise necessitating the stopping of an approaching train, a brakeman, fireman or other party can place the emergency stop, 30 either with or without a flag, at some point in the path of the coming train and stop said train without any volition on the part of the engineer or fireman in charge thereof.

An object of the invention is to provide a 35 device of the class that will be simple, substantial, easily operated and thoroughly efficacious for the purpose designed. With these and other objects in view, the invention will be more fully set forth in the following 40 specification, shown in the accompanying drawings and defined in the appended claims.

The drawings illustrate a preferred embodiment of our invention in which Figure 45 1 is a plan view of our improved train stop installed between the rails on a road bed.

Fig. 2 is a side view of the same, and a cross section of a road bed.

Fig. 3 is a perspective view of our im- 50 proved train stop preparatory to fitting to the T-rails.

In the drawings, like marks of reference refer to corresponding parts in the different views in which A represents the T-rails; B, 55 the ties of a railway road bed; and C, our improved train stop.

The stop in the main comprises two sections, 1 and 2, connected by a pintle 3, and adjustable side brace arms 4 fitted to an upright post 5 forming part of the section 1. 60

The section 1 has an offset extension 6 in alignment with the section 2 and preferably is provided with a depending stud 7 which when the sections are fully extended, as shown in Figs. 1 and 2, will project within 65 or through a correspondingly formed aperture in the section 2 for the purpose of assisting in connection with the pintle 3 to prevent side thrust of the parts when stress is brought to bear on the post 5 when said post 70 engages with train mechanism to operate the brakes, etc.

At either end of the sections 1 and 2 forked extremities 8 are provided to stride the inner bottom flanges of the rails. Preferably one of the sections is provided with an adjustable forked extremity, as 9, for the purpose of affording absolute and minute adjustment of the apparatus to rails of various width flanges. As shown, the adjustable extremity 9 is formed with a couple of elongated slots 10 through one of which a headed stud 11 projects from the section 1, the opposite slot receiving a stud projecting from said section and fitted with a screw-threaded hand lever 12 by which provisions 75 said section may be longitudinally moved with respect to said section 1 and be firmly secured by means of said hand lever. 80

Adjacent to the offset extension 6, a hand-operating latch 13 is pivotally secured to the section 2. This latch has an overhanging lip 14 which when the extension 6 is foldably seated upon said section 2 may be turned to prevent said extension from raising and thereby hold said sections 1 and 2 in alignment between the rails, as shown in Fig. 2. 90

That additional stability may be provided to prevent the post 5 from side thrust, as heretofore mentioned, two adjustable stabilizing arms 4 laterally project therefrom in opposite directions. These arms have longitudinally-formed slots 15 (Fig. 3,) through which a bolt 14 passing through said post projects, one end of the bolt being 100 formed with a head, the opposite end being screw-threaded and fitted with a hand nut 16 by which said arms may be firmly bound to said post when suitably adjusted. These arms at their outer extremities are curved 110 and pointed for the purpose of more readily engaging ties to which they are fitted to

brace said post 5 in the operation of the train stop.

As shown, the post 5 is provided with a socket 17 into which the handle of a signal flag 18 may be placed. An object in placing a flag on the train stop is to give an engineer due warning to slow down and stop, which warning if ignored would result in the stalling of the train should the engineer under-
10 take to pass over the flag.

At night, in dense fog, or on sharp curves in the right of way, an engineer's vision is almost if not entirely of no avail, and to provide a stop under such conditions that
15 will be absolutely infallible for stopping oncoming trains near points where danger is imminent, the present stop has been devised.

While we have disclosed a preferred embodiment of our invention, to those skilled in mechanics it might devolve that certain modifications and details of construction could be resorted to to effect a like result, and we reserve the right to arrange and construct our improved stop in any manner compatible within the limit and scope of our invention.

From the foregoing description, taken in connection with the drawings, a more extended explanation of the objects and advantages of our invention is believed unnecessary.

Having, therefore, explained our invention, what we claim as new and desire to
35 secure by Letters Patent, is:

1. In a device of the class set forth, the combination of portable hinged sections arranged to engage the flanges of the rails of a roadbed, one of said sections having
40 an upright post adapted to engage a pre-arranged device on rolling stock that will automatically bring said rolling stock to a halt when brought in contact with said post, and means to rigidly hold said sections
45 alined between said rails.

2. In a device of the class set forth, the combination of portable hinged sections having slotted extremities adapted to engage the flanges of the rails of a roadbed,
50 one of said sections having an upright post adapted to engage a pre-arranged device on rolling stock that will automatically bring said rolling stock to a halt when brought in contact with said post, and
55 means to rigidly hold said sections alined between said rails.

3. In a device of the class set forth, the combination of portable hinged sections, one of said sections having a slotted ex-
60 tremity, the opposite section having an ad-
justable slotted extremity, said slotted ex-
tremities adapted to engage the flanges of
the rails of a roadbed, a post extending up-

wardly from one of said sections adapted to engage a pre-arranged device on rolling
65 stock that will automatically bring said stock to a halt when brought in contact with said post, and means to rigidly hold said sections in alinement between said rails.
70

4. In a device of the class set forth, the combination of two sections having slotted extremities adapted to engage the flanges of opposite rails in a roadbed, said sections being hinged and arranged to form an abutting contact when brought into alinement, means to rigidly affix said sections in alinement between said rails, and an upright post extending from one of said sections, said post adapted to engage a pre-arranged device on rolling stock that will automatically bring said rolling stock to a halt when brought in contact with said post.
75

5. In a device of the class set forth, the combination of hinged sections having slotted extremities adapted to engage the flanges of opposite rails in a roadbed, said sections being hinged and arranged to abut when brought into alinement between said rails, means to rigidly interlock said abutting sections, an upright post extending from one of said sections, adjustable brace arms extending from said post adapted to engage ties either side of said hinged sections and stabilize said post from lateral movement, substantially as and for the purpose set forth.
80

6. In a device of the class set forth, the combination of a portable apparatus arranged to engage the rails of a roadbed and having an upright post adapted to engage a pre-arranged device on rolling stock that will automatically bring said rolling stock to a halt when brought into contact with said post, and means on said post for receiving the handle of a signal flag, for the purpose set forth and described.
